Wm C. Rodgers Inventor

by W. T. Fitzgerald Attorney.

UNITED STATES PATENT OFFICE.

WILLIAM CRITTINGTON RODGERS, OF OWLET GREEN, TEXAS, ASSIGNOR OF
ONE-HALF TO FRANKLIN P. LYBRAND, OF SAME PLACE.

PORTABLE SAW-MILL.

SPECIFICATION forming part of Letters Patent No. 296,220, dated April 1, 1884.

Application filed December 8, 1883. (No model.)

To all whom it may concern:

Be it known that I, WILLIAM C. RODGERS, a citizen of the United States, residing at Owlet Green, in the county of Van Zandt and State of Texas, have invented certain new and useful Improvements in Portable Saw-Mills; and I do hereby declare the following to be a full, clear, and exact description of the invention, such as will enable others skilled in the art to which it appertains to make and use the same.

The object of this improvement is to produce a portable saw-mill of such cheap and economical plan as can be built and repaired in almost any locality.

The invention consists in the peculiar construction and arrangement of the parts, as will be hereinafter fully explained and specifically claimed, reference being had to the drawings herewith filed as part hereof, and in which similar letters of reference denote like parts.

Figure 1 is a side elevation, partly in section. Fig. 2 is an end elevation with some of the parts removed and some in section, to better illustrate the construction. Fig. 3 represents some of the details partly in section.

A is the track-frame of the mill, which is to be mounted at both ends on transporting-wheels B.

C is an upright post or beam bolted to the frame A, and provided at its upper end with a rectangular projection or bracket, S, which may be affixed to post C by mortise and tenon, as shown at R, or in any secure manner. To the bracket S are affixed journal-boxes, which form bearings for trunnions k of the vibrating box K, which acts as an arbor for the guide-bar I, having eyes at its lower end, to which the upper end of the saw G is affixed by bolts g. Below the track-frame A, and located centrally therewith, are perpendicular beams a", tenoned to the track-frame A, and braced in position by the angled beams a', tenoned to the frame A and to the perpendicular piece a", and further secured in position by cast-iron plates N, which embrace the

joints so formed, and are made fast thereto by wood-screws n. A pair of double-flanged castings, D and D', connected by integral lugs d, are secured in a vertical position to the perpendicular beams a" by the screws d' near their lower ends, and to the frame A by flanged metal plates and wood-screws, as shown at b. A counterpart of the double-flanged casting D is bolted thereto by means of perforated lugs corresponding to the lugs, as shown at d. The double-flanged castings D D', thus united, form an arbor, as shown in Fig. 2, for the cross-head E, to which the lower end of the saw G is secured. Pendent from the cross-head E are plate-links F, to which the pitman P is connected with the saw, thence with the crank H on the shaft M, which is operated by pulley J, to be connected by the usual belt with driving-power. The frame should be elevated sufficiently to clear the machinery both for transportation and operation. The carriage V, for feeding the log T to the saw, is stopped while the log is hoisted to the carriage by means of skids connected with the side of the frame A. The log is fed to the saw automatically by the usual appliance, which is not shown, as no claims are to be made in such regard.

The motion of the driving-shaft M will give action to the saw G, which, by reason of the guide-bar I and vibrating box K, will vibrate to and from the dotted line, as shown in Fig. 1, and clear the cut going and resume it on the downstroke.

Having thus explained the construction and operation of my improvement, what I claim as new, and desire to secure by Letters Patent, is as follows:

1. In a reciprocating saw mill, the vibrating box K and guide-bar I, operating therein, in combination with the saw G, cross-head E, having pendent links F, for connecting with driving-shaft through pitman P and crank H, and the cross-head arbor formed of the plates D D', all constructed and arranged to operate substantially as specified.

2. The mounted frame A, provided with

upright beam C and projection S, perpendicular beams a'' , brace-beams a' , and embracing-
plates N, in combination with the vibrating
box K, guide-bar I, saw G, cross-head E,
5 having pendent links F, and the cross-head
arbor D D', pitman P, and driving-shaft M,
substantially as specified, for the purpose set
forth.

In testimony whereof I affix my signature in
presence of two witnesses.

WILLIAM CRITTINGTON RODGERS.
